UNITED STATES PATENT OFFICE.

WILLIAM W. BRIGG, OF WASHINGTON, DISTRICT OF COLUMBIA, ASSIGNOR
OF ONE-HALF TO PHILIP FELIX HERWIG, OF NEW ORLEANS, LOUISIANA.

LEATHER-CUTTER.

SPECIFICATION forming part of Letters Patent No. 273,019, dated February 27, 1883.

Application filed December 22, 1882. (No model.)

To all whom it may concern:

Be it known that I, WILLIAM W. BRIGG, a citizen of the United States of America, residing at Washington, in the District of Columbia, have invented certain new and useful Improvements in Leather-Cutters, of which the following is a specification, reference being had therein to the accompanying drawings.

My invention relates to certain improvements in devices for forming the leather strips or brushes used in my improvement in cotton-gins, patented October 28, 1879; and the novelty consists in the construction and arrangement of parts, as will be more fully hereinafter set forth, and specifically pointed out in the claims.

This invention embodies improvements on or modifications of the device for which an application for a patent is filed by me of even date with this application; and it has for its object, among others, to form beveled surfaces near the edges of the material formed by the edge-slit—that is to say, the slit which extends into the material at right angles with the edge thereof.

The invention is fully illustrated in the accompanying drawings, which form a part of this specification, and in which—

Figure 1 is a perspective view of my device complete, except that one of the jaws of the clamp is represented as broken away; Fig. 2, a front elevation with the guide-cap removed; Fig. 3, a perspective detail of the transverse cutter, and Fig. 4 a detail view of the clamp and its adjoining parts.

Referring to the drawings, in which similar letters of reference indicate like parts in all the figures, A and B represent two cross-levers, pivoted together at x , the handles of which are held apart by the constant force of a spring, z , as shown. The lever A has a jaw, A', the upper face or bed, A², of which is inclined, and is provided with a longitudinal slot, I, which forms a junction with a transverse slot, c, at its center, said transverse slot being formed between the head or jaw A' and a removable guide-cap, C. A transverse horizontal slot, d, is also formed in the head, in which slot reciprocates the carriage D, carrying the V-shaped or grooving cutter F, a vertical cutter, F', being formed

at the junction of the cutting-edges of the cutter F. Properly pivoted to this carriage is an arm, D', which in turn is pivoted at d² in ears d³, formed on the lever B, near its pivot.

G represents a clamp-lever, the handle of which extends to a point readily reached by the fingers of the operator, that is contiguous to the haubles of the levers A B, and it is provided with bifurcated forward extremities, one of which is pivoted upon either side of the jaw A' at g, and the bearing or clamping jaw G' of which is arranged over the laterally-extending projections a of the jaw-face A².

Secured to the end of the jaw B', in a proper recess, by a screw, h, is the transverse cutter H, which is so curved as to accommodate itself to the arc of its oscillation and the form of the transverse slot c, and it is provided with two inclined cutting-edges, h², each being inclined upwardly and outwardly from the central point, at which is formed a small cutter, h³, projecting inwardly at right angles to the transverse plane of the said cutter H. At or near the center of the cutter is formed a recess, h', the lower portions of which correspond with the form of the reciprocating cutter F and F'.

It will be understood that in the operation of the device the edge of the leather or other material is inserted on the face A² under the clamp G', and as the handles of the levers A and B are forced together the knife-edges h² cut the slit parallel to the edge of the material, and the small cutter h³ makes a small slit at right angles thereto. As the handles are further forced together the grooving or V-shaped cutter F and the vertical cutter F', through their connections D and D', are put in motion, and while the cutter F forms a V-shaped groove from the edge of the material inward, the cutter F' cuts from the bottom of said groove entirely through the material, and when said cutters have approached the slit formed by the cutter H the said cutter H has reached a point which will allow the cutters F F' to pass through the recess h', the cutter F' coming fairly into the slit formed by the small cutter h³ on the knife H. By this operation it will be observed that each edge of the material adjoining the edge-slit is beveled

down, both alike, and that all the grooves are exactly alike, thus forming a much more effectual brush for the purpose required than where the grooves are cut by hand in the usual manner.

As in the devices described in my other application referred to herein, it may be necessary to have the edge-slits of more or less length, and this is readily provided for by employing a scale on the face A^2 , or by having the clamp adjustable by changing the pivot g backward or forward, allowing the edge of the material to abut against the part g' as against a gage, or by using removable jaws of different sizes for the clamp.

As described, the operating means are confined to cross-levers; but it is obvious that the essential elements of the invention would be of equal service if the other manipulating means were employed.

Modifications in details of construction may be made without departing from the principle or sacrificing the advantages of my invention, the essential features of which have been fully described in connection with the illustrations thereof.

By the use of this invention two or three days' time of an expert mechanic can be saved on each and every gin in the application of my before-mentioned improvement on cotton-gins, as by the use of my cutter any novice or inexperienced plantation hand can prepare the leather strip or "brushes" with great rapidity and unfailing accuracy and uniformity that cannot be equaled by the most expert mechanic with the ordinary appliances, which in the one hundred thousand gins to which its use is applicable would save five hundred thousand dollars in labor alone in the first application of my improvement, and a like sum every time said strips were renewed.

What I claim as new is—

1. In a cutting device, the combination, with a grooving-cutter constructed and arranged to cut a groove in the face of the article being operated on, of a knife working at an angle to the motion of the first cutter and constructed and arranged to cut off the end of the material removed from the groove, and suitable means for giving motion to said cutter and knife, all substantially as described.

2. In a cutting device, a V-shaped cutter for making a groove substantially at right angles to the edges of the material, and a vertical cutter for making a slit at the bottom of said

groove, combined with means, substantially as described, for forcing such cutters through the material in one direction and means for retrograding them in the other, as set forth.

3. In a cutting device, a compound cutter composed of a V-shaped cutter for grooving and a vertical cutter for severing the material beneath the groove, both formed in one piece, and constructed and adapted to serve as and for the purpose set forth.

4. In a cutting device, the reciprocating cutter having inclined cutting-edges for forming a slit in the material substantially parallel with the edge and a short slit at right angles therewith, or substantially so, combined with a compound reciprocating cutter for forming the edge-slit and beveling the edges of the material adjacent to such slit, and means for giving motion to said cutters, substantially as and for the purposes set forth.

5. In combination with the knife or cutter H , having inclined cutting-edges h^2 and cutter h^3 , arranged at right angles to the transverse plane of said cutter, the compound cutter F F' , the latter operating in a line with the cutter h^3 , and the bed A^2 , having slots I and c , as and for the purposes set forth.

6. The combination of the cutter H , having recess h' and cutting-edges $h^2 h^3$, with the compound cutter F F' and the bed A^2 , having slots I and c , as and for the purposes set forth.

7. In a cutting device, and in combination with the levers A B and knives H and F F' , the clamps G' , having handle G , arranged and adapted to serve as and for the purposes specified.

8. In a cutting device, and in combination with the pivoted levers A B , the jaw A' , having vertical slots I and c and transverse slots d , the carriage D , reciprocating compound cutter F F' , arm D' , and spring z , for retrograding said cutter, as set forth.

9. The combination of the jaw A' , having slots I , c , and d , arranged as shown, the carriage D , arm D' , and compound cutter F F' , with the jaw B' , carrying cutter H , the clamp G G' , and the spring z , all constructed and arranged to serve as set forth.

In testimony whereof I affix my signature, in presence of two witnesses, this 18th day of December, 1882.

WILLIAM W. BRIGG.
